PENDANT HAVING A TRANSPARENT PRISM FACE

Carl J. Kleiner, 2302 Beach, Cisco, Tex. 76437

Filed July 11, 1974, Ser. No. 537,453

Term of patent 14 years

Int. Cl. D11—01

U.S. CL. D45—17

FIG. 1 is a front elevational view of a pendant having a transparent prism face showing my new design;

FIG. 2 is a real elevational view of said pendant;

FIG. 3 is a right side elevational view of said pendant;

FIG. 4 is a left side elevational view of said pendant;

FIG. 5 is a bottom plan view of said pendant as seen looking up on the view of FIG. 1;

FIG. 6 is a top plan view of said pendant as seen looking down on the view of FIG. 1;

FIG. 7 is a perspective view of the front and bottom of said pendant;

FIG. 8 is a perspective view of the front and top of said pendant;

FIG. 9 is a perspective view of the left, top and front sides of said pendant; and

FIG. 10 is a perspective view of the right, top and front sides of said pendant.

I claim:

The ornamental design for a pendant having a transparent prism face, as shown and described.
